APPARATUS FOR THE CONTINUOUS TREATMENT OF CLOTH

Harold R. Wilcox, Maynard, Mass., assignor to Riggs & Lombard, Inc., Lowell, Mass., a corporation of Massachusetts

Application February 8, 1952, Serial No. 270,539

11 Claims. (Cl. 68—9)

This invention relates to apparatus for the continuous treatment of wet cloth in which the cloth is passed for treatment continuously and successively through a series of treating units, such as tanks, and in which cloth feeding means are provided for each unit.

The object of the invention is to provide novel and efficient means acting to synchronize the feeding operation to enable the continuous passage of the cloth throughout the series of units to be maintained.

The object of the invention is further to provide for the synchronization of the feeding means in the apparatus by an electric circuit conducted through the wet cloth between separated contacts with the circuit thus completed and interrupted by the wet cloth between successive units moving into and out of engagement therewith.

The object of the invention is further to provide novel means for accurately controlling the tension on the cloth passing between successive units.

These and other objects and features of the invention will appear more fully from the accompanying description and drawings and will be defined in the claims.

The nature of the treatment of the cloth and the number of treating units employed may vary widely. The cloth being treated in the apparatus may be in either rope form or in open width. It is therefore unnecessary to illustrate or describe in any great detail the various types of apparatus in which the present invention may be embodied. The principal features of an apparatus for which the invention is suitable are, first, that there be a series of treating units and these may be of any number these treating units must either moisten the cloth or handle previously moistened cloth so that the cloth is wetted to act by its moisture content as a conductor of electricity; second, that there be a variable speed feeding means for each unit in which the speed of the cloth therethrough is to be regulated and with this feeding means controlled to effect synchronization of the feed of the cloth through the series.

This application is a continuation in part of application Serial Number 216,694 filed March 21, 1951, and one form of apparatus for the continuous treatment of wet cloth in rope form is there illustrated in considerable detail.

The drawings herein illustrate sufficiently for the present purpose an apparatus such as illustrated and described in the said application with a preferred form of the present invention embodied therein and also other forms of apparatus and embodiments of the invention.

In the drawings:

Fig. 1 is a side elevation of a portion of an apparatus such as shown in the aforesaid application with two treating units illustrated and with the electric controlling mechanism being shown diagrammatically;

Fig. 2 is an enlarged detail in side elevation particularly to illustrate the contacts and their relation to the cloth running between the units;

Fig. 3 is a detail in elevation looking toward the

2

right of Fig. 2 and also showing the stop motion mechanism in the succeeding tank;

Fig. 4 is a front elevation of the stop motion mechanism shown in Fig. 3 as indicated by the line 4—4 in Fig. 1;

Fig. 5 is a side elevation of a portion of two successive units such as shown in Fig. 1, with another form of the invention embodied therein;

Fig. 6 is a side elevation showing portions of successive units of another form of apparatus particularly adapted for the treatment of cloth in full width and with one form of the invention embodied therein.

The apparatus illustrated in Fig. 1 comprises a series of units of a general type employed in the continuous wet treatment of cloth. The number of the series may vary considerably in accordance with the requirements, but usually ranges from four to nine. Since the construction of each unit is substantially the same it is not necessary to illustrate an entire series.

Each unit is shown as comprising a suitable tank 1 mounted in a suitable framework 2 with the bottom of the tank of the usual curved form. The cloth 3, which is in this type of apparatus preferably handled in rope form, is shown entering the unit at the left of Fig. 1 passing between the feeding and squeeze rolls 4 and 5 over a driven guide roll 6 and thence down on to the curved bottom of the tank, thence upward over a guide roll 7, again through the squeeze rolls and repeating its path in spiral form, finally emerging from the squeeze rolls and passing to the synchronizing mechanism with which this invention is particularly concerned, and then continuing in a similar manner through the other units of the series. The roll 6 is preferably of a ribbed construction and it and the lower squeeze roll 5 are both driven by an electric motor 8, the motor by a chain 9 and sprocket connection driving the roll 5 and the roll 6 being driven by suitable means from the roll 5. Each unit of the series is provided with a similar set of rolls and motor for driving them.

In order that the cloth shall pass continuously through the several units in sequence it is necessary to control the speed of the cloth at the various stages in its operation. In this type of apparatus one of the motors is a leading motor and the motors of the other units have to be synchronized therewith. This leading motor may be either that for the first unit of the series or for the last unit, or even under certain circumstances that for an intermediate unit. Consequently the speed of the cloth delivered from any one unit may regulate either the speed of the feed of that unit or the speed of the feed of the adjacent unit. In the arrangement illustrated in Fig. 1 it is assumed that the leading motor is that for the unit at the left and consequently that the speed of the motor feeding the cloth in the succeeding unit at the right is being regulated to conform therewith.

In the present invention the wet cloth after it leaves the first unit of a pair of units and before it enters the second unit of the pair acts to vary the speed of one of the feeding means to equalize the feed of the cloth through the units and in the illustrated case these means act to vary the speed of the feeding means of the second unit of the pair. This control is effected by an electric circuit conducted through the wet cloth to complete the circuit and to be interrupted by the wet cloth moving from the contact.

In the preferred construction illustrated an idler roller 20, carried by a shaft 21, is mounted to rotate freely in bearings 22 mounted on an upright frame 23 at the exit end of the tank of the first unit, and the cloth 3 in passing from the said unit to the succeeding unit passes over this idler roller, and thence to the feeding rolls of the succeeding unit. A pair of separated electric circuit con-

tacts are mounted beneath the idler roller adjacent the path of the cloth. As shown these contacts are in the form of horizontal bars 24 and 25. The bar 24 is mounted in brackets 26 adjustable longitudinally on arms 27 secured to the frame 23 extending at the front of the idler roller and the bar 25 is similarly mounted in brackets 28 adjustable longitudinally on arms 29 mounted on the frame 23 at the rear of the idler roller. A guide frame 30 at the front mounted on the frame 23 serves to direct the cloth to the idler roller 20.

The electric contacts, consisting of the bars 24 and 25, are contained in an electric circuit acting through suitable means when completed and interrupted to vary the speed of the motor 31, in this case of the second unit. This may be done in any suitable way, but preferably as illustrated by varying the field current of the motor.

One suitable arrangement for thus varying the field current of the motor is illustrated diagrammatically in Fig. 1. The power current entering at 50 is connected to a transformer 51, the secondary 52 of which transforms the current in the circuit 53 to that required for the motor and this circuit contains a rectox 54 changing the current into the direct form required. Another circuit 55 is tapped from the secondary 52 to carry a required voltage of, for example 110 volts. This current contains a transformer 56, the secondary 57 of which is connected to the heating element of the cathode 58 of a thyratron tube. The anode 59 and the cathode 58 are contained in the circuit 60 taken from the secondary of a transformer the primary of which is in the circuit 53. The contacts 24 and 25 are connected, as shown, into the circuit 62 containing the cathode and plate of the thyratron tube and this circuit receives its energy from the secondary 63 of a transformer the primary of which is in the circuit 64 tapped into the secondary 57 with the current rectified by the rectox 65.

It will thus be seen that with the contacts 24 and 25 open the field current for the motor flows through the resistor 66 instead of through the primary 67 of the transformer in the circuit 53 due to high reactance with the open secondary. The minimum field current or maximum speed of the motor 31 is adjusted by the resistor 66. When the contacts 24 and 25 are closed the thyratron tube 59 functions, the secondary of the transformer being short circuited. This causes additional flow of current through the primary 67 of the transformer, thus strengthening the field of the motor and reducing the speed. The maximum field strength of the lower speed is adjusted by the resistor 68.

The basic feature, whatever the arrangement of the circuits and means employed may be, is that the electric circuit for varying the speed of the motor is completed by being conducted through the wet cloth and is interrupted when the wet cloth moves away from the contact. In this case if the speed of the motor 31 is too fast the cloth is pulled up against the contact bars 24 and 25 and when in contact with both the circuit is completed through the wet cloth and the speed of the motor reduced. Then as soon as the reduction in speed causes the cloth to fall away from either one of the contacts the circuit is opened and the speed of the motor increases to its normal amount. Thus the circuit is interrupted and completed through the wet cloth by the up and down movement of the cloth between the two units and thus the feed of the cloth through the two units equalized. The important feature is that the wet cloth engaging the contacts acts itself as a conductor for the current by means of its moisture content.

The arrangement is particularly advantageous because under normal conditions substantially no strain or tension need be placed upon the cloth. It rides freely over the idler roller and feeds continuously and uniformly through the apparatus being brought into and out of engagement with the contacts only as required by the variation in speed. There must, of course, be some tension placed

on the wet cloth to bring it into engagement with both contact bars and thus cause an electric circuit to be conducted through the wet cloth. Further, as hereinbefore pointed out, these bars are both vertically adjustable. The amount of tension thus placed on the cloth is adjustable by adjusting either or both of these bars. With the loop of wet cloth sagging freely there is a minimum—practically no—tension in the cloth while the tension increases as the bars are raised. This feature enables the tension in the cloth passing between successive units to be very accurately controlled.

The unit at the right is shown as illustrated in Figs. 3 and 4 with the means for stopping the operation of the entire apparatus if the cloth for any reason clogs up. For this purpose the cloth is shown as entering the unit through a frame 70 connected to a side wall of the unit and brought into engagement with a bar 71 operating a microswitch 72 to stop the operation in such a case.

Another embodiment of the invention is illustrated in Fig. 5 and is that illustrated in the aforesaid application. Here again a portion of two of the units is sufficient for a disclosure of the invention. In this construction a framework is provided connecting the adjacent units 80 and 81 having the uprights 82 and 83 and the supporting platform 84. A roll 85 is journaled at 86 and driven by a belt or chain 87 from the driven roll 88 of the first unit. A second roll 89 is journaled at 90 on the platform 84. The cloth 3 after leaving the squeeze rolls 91 and 92 driven by the motor 93 passes over the roll 85 and thence over the roll 89 sagging in a loop therebetween, as indicated, and then passes through the adjustable tension device 94 under the guide roll 95 to the squeeze rolls 96 and 97 driven by the motor 98 of the second unit. It will thus be seen that as the speed of the feed varies from the normal the loop of cloth between the rolls 85 and 89 rises and falls.

The platform 84 is provided with a pair of spaced electric contacts 99 and 100 with the space between located opposite the center of the loop of cloth. Thus when the wet cloth engages both contacts the circuit is conducted through the cloth and thus completed. When the wet cloth moves away from either contact the circuit is interrupted. These contacts are, as in the previous case, included in an electric circuit of very weak source and an electronic controlling mechanism which controls the field circuit of the motor 98. The means employed for this purpose may be the same as those already illustrated in connection with Fig. 1 and are therefore indicated by reference to that figure. In this case the motor 98 of the second unit is assumed to be the leading motor and consequently the speed of the motor 93 must be varied as required.

If then the speed of the motor 93 is relatively too great the loop of wet cloth sags into engagement with the contacts 99 and 100 completing the circuit and thus momentarily reducing the speed of the motor 93. As the speed decreases the loop of cloth moves away from the contacts, the circuit is interrupted and the motor speeds up. Thus again there is a continual completing and interrupting of the circuit and the consequent maintaining of the required normal speed of the motor.

In this, as in the previous case, the circuit containing the contacts is very weak and there is no danger of injury to the cloth.

A further embodiment of the invention is shown in a type of apparatus such as employed for the continuous feeding of cloth in full width through successive units of an apparatus. In Fig. 6 a very simple apparatus is shown comprising a portion of two successive units each containing a series of rolls 110 and 111 over and under which the cloth passes for treatment. The unit at the left is provided at the top with a pair of feed rolls 112 and 113 driven by a motor 114 and the one at the right by a similar pair of feed rolls 115 and 116 driven by a motor 117. In this form it is assumed that the motor

of the left hand unit is a leading motor and that of the right hand unit a motor the speed of which is to be regulated. An idler roller 118 is journaled in blocks 119 mounted on arms 126 projecting from the frame 121 of the unit. Contact bars 122, which may be similar to those already described, are mounted on blocks 123 adjustable on bars 124 projecting forward from the frame 121 with the contact bars beneath the idler roller 118. Another idler roller 125 is mounted below the contact bars in brackets 126 on the frame 121.

The cloth 3 in open width form leads between the feed rollers 112 and 113 over the idler roller 118 around behind the idler roller 125, down under the rollers 111, and over the rollers 110 and up through between the feed rolls 115 and 116 of the next unit. With the cloth feeding evenly through the two units it sags away from contact with both of the contact bars 122, but if the speed of the motor 117 is slightly greater than that of the motor 114, so that the cloth is brought into contact with both contact bars 122, the electric circuit in which the contact bars are included is completed through the wet cloth, and this circuit is utilized to decrease the speed of the motor 117. This may be done by any suitable means, but preferably by the same arrangement as that described in connection with Fig. 1 and for that purpose reference is made in Fig. 6 to Fig. 1.

It will be seen that in the first and third forms of the invention illustrated the two contacts beneath the idler roll are mounted one adjacent the path of the cloth leading to the idler roll and the other adjacent the path of the cloth leading from the idler roll, and in each case means are provided for adjusting each contact toward and from the path of the cloth. In the first form this is secured by the adjustment of the contact bars 24 and 25 longitudinally on the respective arms 27 and 29, while in the third form this is secured by adjusting the contact bars 122 on the bars 124. This adjustment also acts to position the contact bars toward and from the idler roll.

This arrangement of the two contacts with respect to the idler roll and the path of the cloth leading thereto and therefrom, with the requirement that the circuit can only be completed through the wet cloth engaging both contacts, prevents any completion of the circuit by reason of the weight of the cloth sagging more or less in its path from the idler roll than in its path to the idler roll. Moreover the adjustment of the contacts enables the feeding tension placed upon the cloth to be controlled as described in connection with the first form. This tension obviously will vary with the distance these contacts are placed from a straight path of the cloth to and a straight path of the cloth from the idler roll.

The term "cloth" is employed herein for convenience but it is to be understood that the invention is not to be limited to the particular nature of the wet material which may be treated and handled in the apparatus.

The invention thus secures the synchronization of the feeding mechanism of the series of units so that the cloth may pass continuously and successively through the series by means controlled solely by an electric circuit completed through the wet cloth and interrupted as the wet cloth moves respectively into and out of engagement with separated contacts as the wet cloth passes from one unit to another.

Having thus described the invention, what is claimed as new, and desired to be secured by Letters Patent, is:

1. An apparatus for the continuous wet treatment of cloth comprising a pair of adjacent tanks, feeding means for each tank acting to feed the cloth successively and continuously through the tanks, a pair of separated contacts, an electric circuit conducted through the wet cloth when the wet cloth between the tanks moves into engagement with both of said contacts and interrupted when the wet cloth moves out of engagement with either of said contacts, and means controlled by the said circuit acting to vary the speed of one of said feeding means to equalize the feed of the cloth through both tanks.

2. An apparatus for the continuous wet treatment of cloth comprising a pair of adjacent tanks, feeding means for each tank acting to feed the cloth continuously and successively through the tanks, a pair of spaced rolls over and between which the cloth passes between the tanks, a pair of separated contacts between and beneath the rolls, an electric circuit conducted through the wet cloth when said cloth between the rolls moves into engagement with both of said contacts and interrupted when the wet cloth between the rolls moves out of engagement with either of said contacts, and means controlled by said electric circuit acting to vary the speed of one of said feeding means to equalize the feed of the cloth through both tanks.

3. An apparatus for the continuous wet treatment of cloth comprising a pair of adjacent tanks, feeding means for each tank acting to feed the cloth continuously and successively through the tanks with the feeding means of one tank having a fixed speed and that of the other having a variable speed, an idler roller between and above the tanks upon which the cloth rests in passing from the one to the other tank, a pair of contacts beneath the idler roll, an electric circuit said circuit being completed through the wet cloth when the feed of the variable speed feeding means is so related to the speed of the fixed speed feeding means as to cause the wet cloth to be drawn into position to engage both contacts, said electric circuit being interrupted when the speed of the variable speed feeding means is so related to the speed of the fixed feeding means as to cause the wet cloth to move out of engagement with either of said contacts, and means controlled by said circuit acting to vary the speed of the variable speed feeding means to equalize the feed of the cloth through both tanks.

4. An apparatus for the continuous wet treatment of cloth comprising a pair of adjacent tanks, feeding means for each tank acting to feed the cloth continuously and successively through the tanks, an idler roller between and above the tanks upon which the cloth rests in passing from the one to the other tank, a pair of separated contacts beneath the idler roll, an electric circuit completed through the wet cloth by the feeding means of the second tank having a speed sufficiently greater than that of the feeding means of the first tank to cause the cloth to be drawn into engagement with both contacts and to be interrupted by a reduction in speed of the second feeding means causing the cloth to be released from engagement with at least one of said contacts, and means controlled by the electric circuit containing the contacts acting to vary the speed of the second feeding means to equalize the feed of the cloth through both tanks.

5. An apparatus for the continuous wet treatment of cloth comprising a pair of adjacent tanks, feeding means for each tank acting to feed the cloth continuously and successively through the tanks, an idler roller between and above the tanks upon which the cloth rests in passing from the one to the other tank, a pair of separated contacts beneath the idler roll, an electric circuit completed through the wet cloth by the feeding means of the first tank having a speed sufficiently less than that of the feeding means of the second tank to cause the cloth to be drawn into engagement with both contacts and to be interrupted by an increase in speed of the first feeding means causing the cloth to be released from engagement with at least one of said contacts, and means controlled by the electric circuit containing the contacts acting to vary the speed of the first feeding means to equalize the feed of the cloth through both tanks.

6. An apparatus for the continuous wet treatment of cloth as defined in claim 3 in which the contacts beneath the idler roll are mounted the one adjacent the path of the cloth leading to the roll and the other adjacent the path of the cloth leading from the roll.

7. An apparatus for the continuous wet treatment of cloth as defined in claim 3 in which the contacts beneath the idler roll are mounted the one adjacent the path

of the cloth leading to the roll and the other adjacent the path of the cloth leading from the roll, together with means for adjusting each contact toward and from the path of the cloth to adjust the tension in the cloth.

8. An apparatus for the continuous wet treatment of cloth as defined in claim 3 in which the contacts beneath the idler roll are mounted the one in front and the other in the rear of the idler roll.

9. An apparatus for the continuous wet treatment of cloth as defined in claim 3 in which the contacts beneath the idler roll are mounted the one in front and the other in the rear of the idler roll, together with means for adjusting each contact toward and from the idler roll to adjust the tension in the cloth.

10. An apparatus for the continuous wet treatment of cloth comprising a pair of adjacent tanks, feeding means for each tank acting to feed the cloth successively and continuously through the tank, a pair of separated contacts, an electric circuit of sufficiently low energy not to injure the cloth, said electric circuit being completed through the wet cloth when said wet cloth between the tanks moves into engagement with both of said contacts, said electric circuit being interrupted when the wet cloth between the tanks moves out of engagement with either of said contacts, means operated by power of relatively high energy for varying the speed of one of said feeding means, and means operated by said circuit acting to control the operation of said power operated means to effect the equalization of the feed of cloth through said tanks.

11. Apparatus for the continuous wet treatment of

cloth comprising a pair of adjacent tanks, electrically driven feeding means for each tank to feed the cloth successively and continuously through the tanks, a pair of spaced rolls over and between which the cloth passes between tanks, and control means for varying the electric power supplied to one of said feeding means to vary the speed thereof whereby to equalize the feed of cloth through both of said tanks, said control means comprising an electric circuit including a normally non-conducting electron discharge tube having at least an anode, a cathode, and a grid, a pair of spaced contacts electrically connected in the cathode grid circuit of said electron discharge tube, said contacts being located on opposite sides of one of said rolls, said tube being rendered conductive when said spaced contacts are both engaged by said wet cloth and being non-conductive so long as said cloth is out of engagement with either one of said contacts.
